UNITED STATES PATENT OFFICE.

ROBERT M. GALLANT, OF BOSTON, MASSACHUSETTS, ASSIGNOR OF ONE-HALF TO
WALTER S. BERRY, OF BOSTON, MASSACHUSETTS.

STOCKING PROTECTOR.

Application filed May 17, 1926. Serial No. 109,555.

My invention relates to women's wearing apparel and more particularly aims to provide a simple, inexpensive and efficient means for protecting the stockings during outdoor wear, especially under conditions of wet streets and sidewalks.

In the drawings, wherein I have shown by way of example an embodiment of one form of my invention:—

10 Fig. 1 illustrates a device in accordance with one form of my invention, the same being there shown in flattened position, viewing its outer surface;

15 Fig. 2 is a side elevation of the device but showing its position upon the wearer;

Fig. 3 is a front elevation of the device in the position as worn; and

20 Fig. 4 shows the lower portion of a modified form of my invention.

25 In the illustrative views I have indicated at 1 a shield, protector or like covering element adapted to fit snugly over the calf and ankle portions of the leg. Said shield may be of any desired length but preferably extends from the heel well up toward the knee, or at least a sufficient distance to cover the portion of the stocking which is normally exposed below the dress. Circumferentially the protector or shield extends at least over 30 the rear portion of the leg and is carried forward at the sides of the leg to any desired extent but leaving the front of the stocking uncovered. It is found that substantially all of the spotting and staining of the stockings 35 in the course of ordinary outdoor wear, particularly under conditions of rain or storm, wet sidewalks, etc., occurs at the back of the stockings, whether resulting from splashes of water, dirt and the like thrown up by the 40 feet of the wearer while walking, or by the feet of other pedestrians, or by spattering and splashing from passing vehicles. The front portion of the stockings, or a major part thereof, may therefore be left un-

45 covered, partly for the reason stated, and more particularly for the purpose of ventilation and comfort to the wearer of the protective device. By said open front construction also the stocking retains substantially its 50 normal appearance as viewed from in front of the wearer of my shield or protective device.

Said shield or cover element 1 may be formed of any suitable flexible sheet material, preferably of light weight and desir-

ably moisture resisting material, such as rubber, or rubberized or other fabric. In the form illustrated I have indicated a light weight, woven fabric in which the warps and wefts are arranged at a substantial angle 60 with the vertical median line of the protector, as seen at 2 in Fig. 1, said fabric desirably being moisture-proofed in any suitable manner. Said bias formation affords additional elasticity for the protector in both transverse 65 and longitudinal directions, particularly the former.

As best seen in Fig. 2, the protector is shaped to conform to the leg portion to be covered, being fashioned to the desired configuration in any suitable manner, either from a single piece of material or from a plurality of mating pieces seamed or otherwise joined as indicated at 3. The protector, as viewed in Fig. 1, is of decreasing width to 70 toward its lower end, being approximately shield-shaped in the form illustrated. The edges of the protector are finished in any suitable manner, as by the side edge binding strips 4, 4, preferably elastic or bias tape, and 75 by similar bindings 5, 6 at the bottom and top edges. If desired such edging, which need not be elastic in all cases, may be continuous about the entire periphery of the protector, or in some instances may be dispensed with. 80 Although generally unnecessary because of the open or skeletonized form of the protector, additional ventilating means such as the vents or eyelets 7, 7, Fig. 1, may be provided at suitable points, such as in the seam, if any. 85 From an inspection of Fig. 3 it will be seen that the inner face of the protector or shield is entirely smooth, being free of any objectionable seam, ridge, or other surface irregularity. 90

95 Suitable means is provided for securing the protector in position on the leg of the wearer and in such manner as to permit of easy and quick putting on or removal. In the present instance I have shown for this 100 purpose tape-like supporting members 8, 8, desirably elastic, one of which is at or near the upper edge of the protector and may be an integral extension of the upper edge binding 6. Any suitable plurality of such fastening 105 tapes may be provided and in this instance I have indicated, in addition to said upper tape, a second and usually shorter tape at substantially mid-length of the protector. Said supporting members may be elastic 110

pieces permanently secured at their opposite ends, or provision may be made, as in the drawings, for releasing one or more of said members at any suitable point in their 5 length.

Said securing members are preferably adjustable in length whereby the protector may readily be accommodated to different leg sizes. I have accordingly shown said members as tapes secured at one end to the protector and having their opposite ends doubled back and attached to slidable buckles or like members 9, 9. At the outer ends of the loops so formed are suitable fasteners 10 such as hooks, loops or the like, as indicated at 11, adapted to cooperate with fastening means 12, 12 at corresponding points at the opposite side edge of the protector.

At or near the lower extremity of the 20 protector is a heel strap 13 preferably of elastic tape secured as at 14, 14 and adapted to receive the wearer's heel. As clearly seen in Fig. 2, said strap 13 passes beneath the instep of the foot and serves to prevent dis- 25 placement of the protector in the direction of its length and to retain the same snugly about the heel and ankle. It will be understood that each pair of the protective devices as above described may be made to in- 30 clude a "right" and "left", the securing means being arranged to fasten at the outer side portions of the respective leg or, if desired, the two devices constituting a pair may be substantially identical, a portion of 35 each securing tape being carried by the opposite side edges so as to provide for fastening at or near the front of the leg.

In Fig. 4 I have shown a modified form 40 for the lower portion of the protector, in- cluding a heel enclosing section or cup-like portion 15 into or through which the heel may be inserted, thus affording protection for the shoe heel as well as the stocking, but without detracting from the ease with which 45 the device may be put on and removed.

With a construction and arrangement such as illustrated and described by way of example, making provision for extreme flexibility and freedom from undesirable binding 50 or undue heating, due largely to the extensive open area at the front of the protector, the resulting article is not only highly effective for the purpose intended but is entirely comfortable in use. The disclosed stocking protector may be manufactured at little ex- 55 pense and with the requirement of a minimum amount of material. It is so designed that it does not detract from the appearance of the wearer, a consideration of importance 60 in this art, it being trim and close fitting as viewed from behind, while leaving the stocking with substantially its normal appearance as viewed from in front.

I am aware that it has heretofore been 65 proposed, as disclosed in the United States

patent to Howard et al., dated January 2, 1877, to provide a guard or protector for the lower extremities of men's "pantaloons" legs, comprising a heavy, boot-like guard device, with integral heel socket, and permissibly 70 formed of leather material, and I make no claim thereto, my invention comprising a flexible, light-weight, shield-like device for wear closely over the rear ankle and calf portions of a woman's leg, directly over the 75 stocking.

My invention is not limited to the particu- 80 lar illustrative embodiment thereof shown and described herein, its scope being set forth in the following claims.

Claims:

1. A woman's stocking protective device comprising a shield or cover element fashioned to fit the calf and ankle portions of the leg, and terminating rearwardly of the shin, said element formed of flexible sheet material and being in major part elastic, at least in the direction transversely thereof, securing means extending from one side edge of said shield or cover element near its top and having a fastener, cooperating fastener-engaging means at the opposite side edge of said element, similar securing and fastening means therefor at a lower portion of said side edges, and a cross-member at the bottom portion of said element adapted to be engaged beneath the wearer's shoe.

2. A woman's stocking protective device comprising a shield or cover element of flexible sheet material of decreasing width toward its lower end, said element being fashioned to fit the calf and ankle portions of the leg and terminating rearwardly of the shin, the material being elastic at least in the direction transversely of said element, an edge binding for said element, said binding for at least the top and bottom edges being elastic, an elastic securing tape integral with the top edge binding and having at its outer end a fastener, a cooperating fastener-engaging member at the opposite side edge of the device, one or more similar securing tapes at a lower point or points on the side edges, and a strap at the lower edge of the device adapted to extend beneath the foot from side to side.

3. A woman's stocking protective device comprising a shield or cover element of flexible sheet material fashioned to fit the calf and ankle portions of the leg and terminat- 120 ing rearwardly of the shin, the material being elastic at least in the direction transverse of said element, an edge binding for said element, said binding for at least the top and bottom edges being elastic, one or more 125 elastic tape-like members at one side edge of the device and having fastener means at their outer portions, cooperating fastener re- ceiving means correspondingly positioned on the opposite side edges of the device, and 130

means for adjusting the length of said tape-like member or members.

4. As a new article of manufacture and wear, independent of a shoe or the like, in combination, a shield for the lower rear portions of a woman's stockinginged leg, said shield being formed of flexible sheet material, open at the front, and being in major part elastic, at elast in the direction trans-

versely thereof, one or more devices for 10 cross-connecting the front edge portions of the shield, and a cross-member at the lower portion of the latter cooperating to retain it in wearing position.

In testimony whereof, I have signed my 15 name to this specification.

ROBERT M. GALLANT.
